(57) **CLAIM**

We claim the ornamental design for a display screen with graphical user interface, as shown and described.

DESCRIPTION

FIG. 1 is a front view of display screen with a graphical user interface showing our new design;

FIG. 2 is a front view of a second embodiment thereof, shown enlarged and separately for clarity of illustration;

FIG. 3 is a front view of a third embodiment thereof, shown enlarged and separately for clarity of illustration;

FIG. 4 is a front view of a fourth embodiment thereof, shown enlarged and separately for clarity of illustration;

FIG. 5 is a front view of a fifth embodiment thereof, shown enlarged and separately for clarity of illustration; and,

FIG. 6 is a front view of a sixth embodiment thereof, shown enlarged and separately for clarity of illustration.

The broken line showing of the display screen and the broken line showing of the portions of the user interface are included for the purpose of illustrating unclaimed environment and form no part of the claimed design.
